UNITED STATES PATENT OFFICE.

WILLIAM H. CURTICE, OF LOUISVILLE, KENTUCKY.

DESIGN FOR A FLOUR-TANK.

SPECIFICATION forming part of Design No. 28,718, dated May 24, 1898.

Application filed April 18, 1898. Serial No. 678,086. Term of patent 14 years.

To all whom it may concern:

Be it known that I, WILLIAM H. CURTICE, a citizen of the United States, residing at Louisville, in the county of Jefferson and State of Kentucky, have invented and produced a new and original Design for a Flour-Tank; and I do declare the following to be a full, clear, and exact description of the same, reference being had to the accompanying drawing, forming a part thereof.

My invention relates to a design for a flour-tank; and it consists in the configuration of the tank, substantially as illustrated in the accompanying drawing.

5 The figure in the drawing hereunto annexed is a perspective view of the flour-tank embodying my design.

The essential features of my design are contained in the following description:

o The circular base which supports the rectangular case has vertical parallel sides, a

vertical front and back, the upper portions of which converge to the horizontal top, upon which rests the inverted conical hopper, upon which appear a horizontal series of parallel 25 duplex rings. A horizontal open cylindrical sleeve with a notch in its upper edge projects laterally from the lowermost conical section of the hopper. A crescent-shaped rail appears on the circular base on the side of the 30 rectangular case.

Having thus fully described my invention, what I claim, and desire to secure by Letters Patent of the United States, is—

The design for a flour-tank, substantially 35 as herein shown and described.

In testimony whereof I affix my signature in presence of two witnesses.

WILLIAM H. CURTICE.
